McLatchie, Tuberose, Saskatchewan, Canada

Application July 31, 1939, Serial No. 289,687

4 Claims. (Cl. 209—401)

My invention relates to improvements in chaffer-screens for use in association with grain threshing machines or combines, an object of this invention being to provide a device of the character herewithin described which in proportion to its over-all dimensions provides a greater perforated area than is to be found in threshing machines of conventional design for deflecting an air blast therethrough.

A further object of my invention is to provide a chaffing screen of the character herewithin described in which there are no horizontal surfaces upon which grain may slide uselessly while the associated machine is in operation and the screen oscillating.

A further object of my invention is to provide a chaffing screen of the character herewithin described in which there are no surfaces, pockets or recesses upon or in which kernels of grain may jump about idly without gravitating downwardly to the conveyor trough.

A further object of my invention is to provide a chaffing screen of the character herewithin described by the use of which, due to the deflector design thereof, it is possible for a forced draught of air to penetrate a deeper bed of material above the screen than is possible by the use of chaffing screens of conventional design thereby preventing "loading" or "drifting" and the consequent loss of grain caused thereby.

A further object of my invention is to provide a chaffing screen of the character herewithin described by the use of which in association with a combine, greater efficiency is obtained during a deviation of the machine from the horizontal or during movement thereof over uneven ground.

A further object of my invention is to provide a chaffing screen of the character herewithin described by the use of which in association with a combine and when engaged in "straight combining" less trouble is experienced with sap from green weeds travelling through the combine with the ripe grain.

A further object of my invention is to provide a chaffing screen in which frame-spanning strengthening members of thick section are eliminated, such members reducing considerably the effective area and accordingly, separating efficiency.

A further object of my invention is to provide a chaffing screen of the character herewithin described which is simple and economical to manufacture, easy to install, requiring no adjustment and which cannot become out of order.

With the above more important objects in view

and such other minor objects as may appear as the specification proceeds, my invention consists essentially in the arrangement and construction of parts all as hereinafter more particularly described, reference being had to the accompanying drawings, in which:

Figure 1 is a perspective view of my improved chaffing screen.

Figure 2 is a side view of the chaffing screen illustrated in Figure 1.

Figure 3 is a side view of my chaffing screen in situ within a threshing machine and showing the adjacent parts of a threshing machine to indicate the relative position of my screen therein.

Figure 4 is a full sized dimensioned section of one of my air draught deflectors.

In the drawings like characters of reference indicate corresponding parts in the different figures.

My invention comprises a rectangular frame 1 designed to oscillate in the direction of the longer sides 2 in the conventional manner, the speed of such oscillation being approximately two hundred and twenty-five throws per minute, each of about three inches in length.

Spanning the sides 2 and therefore normal to the direction of oscillation of the frame, is a plurality of parallel air stream deflectors 3, each of which comprises what I term as a "steep draught over-plate" 4, a "shallow draught under-plate" 5 and a low pressure, connecting shelf 6, the deflectors being preferably manufactured of one piece sheet metal. It will be noted that my over-plate 4 is of greater width than the under-plate 5, the approximate width of the former being two and one-eighth inches while that of the latter is approximately one and three-eighths so that the over-plate projects upwardly beyond the under-plate and hoods the same.

It will be noticed that the obtuse angulation above the horizontal, of my shallow draught under-surface 5 (considered from the fan side of my chaffing screen) is greater than that of the over-plate 4, the angulation which the former makes with the horizontal being approximately 152°, while that which the latter makes is approximately 134°.

The width of my low pressure shelf 6 is approximately three-eighths of an inch while the width of the upper portion of my over-plate, or in other words, the width from the upper edge thereof down to the line where it meets the inner edge of the low pressure shelf, is seven-eighths of an inch.

By reference again to the accompanying Fig-

ure 4, it will be noted that when my air stream deflectors are manufactured from one piece sheet metal that the under-plate 5 and shelf 6 are maintained in their correct relative positions to the over-plate 4 by angulating the sheet metal again to form the lining strip 7, around the edge of which the sheet metal is formed to provide a beaded edge 8.

It will be noted that the over-plate 4 and the under-plate 5 converge to form a wind screen cutting edge 9 and at this point I would state that the edges 9 of each of my wind screen deflectors are spaced three inches apart, from which it will be seen that since the throw of the screen during operation is three inches also, the deflectors will move back and forth and no portion of the area within the frame can escape being traversed by my deflectors.

I would finally mention in connection with my wind stream deflectors that extending through the triangulated hollow center of each, is a tie-rod 10, to assist in holding the sides 2 together and although various methods may be resorted to to maintain my wind stream deflectors at the correct degree of angulation with respect to the horizontal, the most satisfactory and economical is probably to provide a rivet head 11 at one end of each tie-rod while screw-threading the opposite end and then wrenching a nut 12 tight over the screw-threaded portion and against the sides so that each deflector is cramped into position.

Spanning the end members 12 are a number of straw and chaff interceptors 13 in the form of parallel round wires spaced half an inch apart and thus running in the direction of oscillation of the chaffing screen. It is immaterial whether each of these wires is a separate wire and secured at each end as by means of a staple for instance, in the end members, or whether a continuous wire is employed and threaded back and forth between the end members but it should be noted that the wires extend through a plurality of aligned holes punched through the steep-draught over-plate 4 of my wind screen deflectors slightly above the point where the inner edge of the low pressure shelf 6 meets it.

By reference to the accompanying Figure 3 wherein I have shown the adjacent parts of a threshing machine in order to assist in explaining the position occupied by a chaffing screen therewithin, that a wind screen from the fan housing 14 of the threshing machine passes through or around the conventional lower screen 15 and is then split or divided by the edges 9 into a plurality of steep draughts of air indicated by the arrows 16 and also into a plurality of shallow draughts of air indicated by the arrows 17.

Thus it will be seen that between the steep and shallow draughts there are areas of low pressure above each of the pressure shelves 6, through which grain may drop into the conveyor trough 19 prior to being elevated by the conveyors 20.

The particular nature of the up-draught through my improved chaffing screen is such that grain is precipitated therethrough without loss and without being carried off by the air stream through the blower and into the straw pile while straw and chaff is more effectively blown off by the use of this screen than is the case with those of conventional design.

In the accompanying Figure 3, the groups of

arrows 21 and 22, represent the path of straw and chaff from the straw-walkers 23 and the tray 24. In this figure also it will be understood that the portion designated by the numeral 25 represents the sheaf intake conveyor while the numeral 26 designates a conventional threshing cylinder through which material is deposited onto the corrugated tray 27. Finally I would mention that the path generally designated by the numeral 28 represents the conventional tailing trough and tailing elevator, such parts being illustrated solely for the purpose of locating my novel chaffing screen within a threshing machine.

Since various modifications can be made in the above invention, and many apparently widely different embodiments of same, made within the scope of the claims without departing from the spirit and scope thereof, it is intended that all matter contained in the accompanying specification shall be interpreted as illustrative only and not in a limiting sense and I desire only such limitations placed thereon as are specifically expressed in the accompanying claims.

What I claim as my invention is:

1. A chaffing screen for use in combination with a grain threshing machine or combine comprising an oscillating rectangular frame and a plurality of wind stream deflectors spanning said frame, each of said wind stream deflectors having a shallow draught under-plate and a steep draught over-plate, said over-plate projecting upwardly beyond said under-plate and hooding the same, said under-plate and said over-plate being positioned at an obtuse angle to the horizontal with respect to the source of said wind stream, the obtuse angulation of said shallow draught under-plate being greater than the obtuse angulation of said steep draught over-plate, said plates converging downwardly to form an air stream cutting edge, and a connecting shelf extending between the upper edge of said under-plate and a line extending medially of the width of said over-plate.

2. The chaffing screen as defined in claim 1 which includes a plurality of straw and chaff interceptors in the form of parallel wire stringers spanning said frame.

3. The chaffing screen as defined in claim 1 in which said wind stream deflectors span said frame at right angles to the direction of oscillation thereof and which includes a plurality of straw and chaff interceptors taking the form of parallel wire stringers spanning said frame in its direction of oscillation.

4. A chaffing screen for use in combination with a grain threshing machine or combine comprising an oscillating rectangular frame and a plurality of wind stream deflectors spanning said frame, each of said wind stream deflectors having a shallow draught under-plate and a flat steep draught over-plate projecting upwardly beyond said under-plate, each of said under-plates and each of said over-plates being positioned at an obtuse angle to the horizontal with respect to the source of said wind stream, said over-plate hooding said under-plate, the obtuse angulation of said under-plate being greater than the obtuse angulation of said over-plate, said plates converging downwardly to form an air stream cutting edge.

CLAUDE M. BREMNER.
